UNITED STATES PATENT OFFICE

THEODORE HENRY LANDGRAF, OF ATLANTA, GEORGIA

MAIL BOX AND HOUSE-NUMBER-DISPLAY DEVICE

Application filed May 1, 1929. Serial No. 359,598.

Generically this invention relates to transparencies or illuminated signs, but it more especially comprehends an illuminated mail box for displaying the particular house or 5 address number associated therewith.

An important object of this invention is the provision of a mail box attachable to a wall, door frame or other support of a dwelling or other building, formed with an illuminating chamber and removable transparent closure, said closure bearing the house or address number associated with said box, and means for illuminating said chamber whereby the number is plainly visible from 15 the approach to said dwelling.

A further object of this invention is the provision of an illuminated mail box of this character for displaying a particular house number, having means for mounting the box 20 in the wall of a building and means for effecting the illumination thereof from within the dwelling or other building.

With these and other objects in view, which 25 will become apparent as the description proceeds, the invention resides in the construction, combination and arrangement of parts, hereinafter more fully described and claimed, and illustrated in the accompanying drawings, in which like characters of reference 30 indicate like parts throughout the several figures, of which:

Fig. 1 is a perspective view of my improved illuminated mail box;

Fig. 2 is a vertical section on line 2—2 of 35 Fig. 1;

Fig. 3 is a detailed view of the closure bearing the house number and manner of mounting same; and

Fig. 4 is a fragmentary elevation of a portion 40 of the mail box showing attaching flange.

In the delivery of mail the postman is often inconvenienced by the obscure numbering of residences and rendering it necessary to obtain the numbers of adjoining houses to 45 ascertain a particular house number, especially at night.

Because of the often obscure locations of 50 house numbers and meagre exterior lighting effects, their proper display is effected only through considerable expense and difficulty,

and it was to overcome such deficiencies and to provide at nominal cost a mail box constituting an illuminated house and address number device adapted to be conveniently located so as to be readily discernible as the 55 entrance of the dwelling or building is approached, and adapted for ready removal and easy installation where change of address becomes necessary that I designed the illuminated mail box device adapted to display its 60 identifying house number, forming the subject matter of this invention.

In the illustrated embodiment characterizing this invention there is shown a mail box 1 formed with conventional door 2, name plate 65 3, mail slot 4 and associated flap 5 of conventional design. The upper section of said box 1 is formed with chamber or compartment 6 in which is mounted incandescent lamp 7 attached to insulated electric cord 8 and controlled by switch 9 for effecting illumination of said chamber. The cord 8 is introduced into chamber 6 through opening 10 in the rear wall of the mail box. The operating knob 11 of switch 9 is adapted to extend through 70 aperture 12, in the present instance, located in the end wall of the box but which may be otherwise positioned as desired. While the box proper may be constructed of any desired material it is preferably constructed from 75 sheet metal, and in the present instance, its front wall is stamped to form a design 13.

Chamber 6 is formed with an opening 14, the bottom 15 of which constitutes a seat adapted to support closure member 16 formed 80 with transparent numerals 17 secured therein by frame 18 secured over the rear edges of said closure by screws 19 threadedly engageable with said plate, as will be clear without further discussion. The closure 16 may be 85 formed in one glass piece or other transparent element, with its body surrounding the numeral 17, painted or otherwise rendered non-transparent as 20, or it may be formed of a plurality of sections *a*, *b*, *c*, and *d*, each section bearing an individual numeral, so that 90 the numbers may be readily changed and easily positioned as desired.

The brackets 21 for holding papers or other matter not insertable in slot 4 are riveted or 100

otherwise suitably secured to the rear wall of box 1. Though the box may be attached to the wall of the building in any suitable manner, in the present instance, its rear wall adjacent its upper end is formed with a bayonet slot 22 adapted to receive a screw head or other element suitably mounted in the main supporting medium.

The modified form illustrated in Fig. 4 is similar to the form above described with the exception that it is provided with a flange 23 constituting an additional means of attachment and preventing its dislodgment when mounted in the wall of a building or the like.

From the above it is apparent that I have designed a unique mail box designed to also display its identifying house number, simple in construction, manufacturable at only a slightly increased cost over the box alone, capable of being easily installed and efficient for the purposes intended.

Although in practice I have found the form of my invention illustrated in the accompanying drawings and referred to in the above description as the preferred embodiment is the most efficient and practical; yet realizing that conditions concurrent with the adoption of my device will necessarily vary, I desire to emphasize that various minor changes in details of construction, proportion and arrangement of parts, may be resorted to within the scope of the appended claim without departing from or sacrificing any of the principles of this invention.

Having thus described my invention, what I desire protected by Letters Patent is as set forth in the following claim:

A combination mail box and house number display device comprising a substantially rectangular casing having a partition dividing the same into a mail receptacle formed with a slot adjacent its upper end and an opening intermediate the slot and lower end and an illuminating compartment formed with a rectangular opening intermediate said slot and upper end of said casing, a flap closure for said slot and hinged closure for said lower opening having means for receiving name indicia, transparent number elements adapted to be supported by said partition and forming a closure for the opening in said illuminating compartment, a frame within said compartment and circumscribing said rectangular opening, said frame embodying means for detachably securing the transparent elements in operative position, an illuminating device mounted on the rear wall of the illuminating compartment, means mounted exteriorly of the casing for controlling the illuminating device, and a removable top closure for said casing.

This specification signed this 26th day of March, A. D. 1929.

THEODORE HENRY LANDGRAF.
